UNITED STATES PATENT OFFICE.

ADELARD J. THERRIEN, OF LYNN, MASSACHUSETTS, ASSIGNOR TO A. J. THERRIEN & CO., INC., OF LYNN, MASSACHUSETTS, A CORPORATION OF MASSACHUSETTS.

PATTERN HOLDER FOR GRADING MACHINES.

Application filed December 24, 1925. Serial No. 77,674.

My invention relates to means for the proper positioning and securing of model patterns on the holding plate of a pattern-grading machine. The particular embodiment of the invention here illustrated is designed and adapted to be used in the manufacturing, grading and cutting of shoe patterns. It will be understood that the illustration shows merely one embodiment of the invention adapted to a special use and is not intended as a limitation of the invention either as to its specific construction, or to any specific use.

The objects of my invention are to provide positive means for positioning and fixing model patterns on a holding plate; to eliminate the use of flags and attachments on model patterns; to provide for the machine production of finished patterns, obviating the hand finishing heretofore required; to eliminate the bolting process heretofore resorted to in pattern making; to eliminate the bolt locating and the marking and punching of bolt holes in model patterns; to eliminate the use of elevating washers on pattern-grading machines; to provide improved adjustable fixing points adaptable for ready relocating on the holding plate; to provide improved means for the relocating of fixing points on the holding plate; to provide improved fixing points; to provide an improved fixing point carriage and punching arm; to materially reduce manufacturing costs resulting from the saving of time and materials; and to provide the various other advantages and results made apparent from the following specification:

I accomplish the objects of my invention as shown in the accompanying drawings which form a part of this specification and in which, Figure 1 shows a pattern secured to the holding plate by means of fixing point carriages positioned thereon. Figure 2 shows the fixing point carriage adaptable to slide in the grooves of the holding plate shown in Figure 1. Figure 3 is a sectional view of the fixing point carriage on the line A—A in Figure 2. Figure 4 shows the hinged punching arm adaptable for mounting on the fixing point carriage shown in Figure 2. Figure 5 shows a side view of my assembled fixing point carriage and punching arm. Figure 6 is a sectional view on the line 6—6 of Figure 1.

Referring again to Figure 1, B shows the

body of the holding plate. C shows the dovetail spaces forming grooves on the plane of said plate. D shows a series of transverse grooves or lines, hereinafter called grooves, on the surface of the holding plate designed for use in conjunction with the groove M¹ shown in Figure 4, in the proper positioning of model patterns on the holding plate for what is known as centergrade work. B¹ shows screw holes through which the plate is secured to the frame of the grading-machine. B² shows an orifice at the working center of the holding plate.

Referring again to Figures 2 and 3, E shows the wedge shape base of the fixing point carriage, adaptable to fit and slide as a dovetail tenon in the spaces C shown in Figure 1. F shows the locking screw positioned in the threaded orifice F¹ shown in Figure 3, a tightening of which screw secures the carriage where positioned, accomplishing this as the end of the screw F presses against the bottom of the spaces C shown in Figure 1. G shows the valley in which fits the hinge mounting H, (shown in Figure 4). I shows the well into which fits the post J on the hinge mounting H, (shown in Figure 4). K shows the base of the punch point L, which base fits into the receptacle K¹ shown in Figure 3 and is interchangeable with other base carrying punch points of varying shapes. The base K extends above the upper surface of the carriage base E so as to hold the pattern, positioned on the punch point L, away from the surface of the holding plate, thus eliminating the use of loose washers to effect this purpose. K² shows an opening available for ready convenience in the application of pressure from the underside when removing the base K for interchangeable or replacement purposes.

Referring again to Figure 4, J shows the post on the hinge mounting H, which post fits into the well I shown in Figures 2 and 3. M shows the punching arm, hinged by the pin N in the orifice H¹ on the mounting H. O shows the base of the female unit P into which unit fits the punch point L, shown here in half circle form, but optionally varied to circular, square, oblong, diamond, cross, triangle or other shape to fit the style of punch point used. O¹ shows an opening available for ready convenience in the application of pressure from the underside in

removing the unit O for interchangeable or replacement purposes. M¹ shows a groove on the punching arm M, preferably positioned so as to register over the center of 5 the groove C thereunder, designed for use on centergrade work in conjunction with the transversal grooves D in the proper positioning of model patterns on the holding plate.

10 Referring again to Figure 5, M² shows the position of the punching arm when swung back from the punch point L, as shown in Figure 1.

Referring again to Figure 1, B shows the 15 holding plate with a pattern Q secured in position thereon by my improved means and showing the various arms M respectively in the punching position with the female unit P over the punch point L, in a midway 20 raised position, and in the extreme open position lying substantially parallel to the holding plate. After the punching process, comprising a closing of the female unit O over the point L, by which closing the pattern is forced and held onto the points L, the arms M may be raised as shown in Figure 1, or optionally removed from the holding plate by detaching the post J from the well I in the base E.

30 In centergrade work, for improved results and major time savings, in preparing to advantageously and accurately locate the model pattern on the holding plate, a complete experimental pattern is first positioned 35 on the plate with the throat of the vamp at the center B². Line markings are then made on the various parts of the experimental pattern following the transversal grooves D on the holding plate, and additional line markings 40 at the groove M¹. These markings on the various parts of the entire experimental pattern disclose the exact positions on the holding plate of what later comprise the various disjointed parts of the experimental pattern. 45 These positions are significantly important after the experimental pattern is divided for example into what is known to the trade as the foxing, the quarter, the saddle and vamp, or such other parts as may be 50 designed. The identical markings on the experimental pattern are then transferred to the model patterns and the correct positioning thereof on the holding plate is assured by matching up said markings with the 55 transverse grooves D and the groove M¹ herein before referred to.

It is possible to eliminate the punching arm M and female unit P, using in place thereof a mallet or hammer of wood or other 60 soft material, a blow from which on the portions of the pattern contacting with the fixing points L forces the pattern onto the fixing points where they are held in use. The punching arms and female units are found however, in practice, to be much more effi-

cient and satisfactory. It is also possible to eliminate the grooves C in the holding plate, substituting therefor a series of orifices into which may be inserted holding posts projecting from the underside of the fixing 70 point carriage. I assume all such and other variations and equivalents as may be construed to fall within the scope of the appended claims.

Having thus described my invention I 75 claim as new and desire to secure by Letters Patent of the United States of America:

1. In a device of the kind described, a holding plate, a plurality of movable members, means for adjustably fixing said members to the holding plate for placement at certain points thereon, a fixing point carried by each movable member and adapted to pierce and hold a pattern placed thereon, said points being bodily removable from said 80 movable members.

2. In a device of the kind described, a holding plate formed with a plurality of grooves, members adapted for slidable engagement in the grooves, means on each 90 member for locking the members in adjusted position in its respective groove, a fixing point carried by each member and removable therefrom, and a removable arm carried by each member and having separable hinge 95 connection therewith for forcing a pattern onto the points.

3. A pattern holder for grading machines comprising a plurality of members each formed with two pivotally connected sections, a holding plate having a series of parallel grooves each for receiving one of said members, and one section of each member being mounted for adjustment along its respective groove on the holding plate, a fixing point on each of said latter sections, and the remaining sections being adapted to be pressed down to force a pattern onto the points, each remaining section each having a recess for receiving its respective point. 100

4. A pattern holder for grading machines comprising a plurality of members each formed with two sections, a separable hinge connection for the sections of each member whereby they may be detached, a holding plate having a plurality of parallel grooves therein, and one section of each member receivable in a groove for adjustment on the holding plate, a fixing point removably carried by each of said latter sections, and the remaining sections adapted to be pressed down to force a pattern on the points. 115

5. In a device of the kind described, in combination, a holding plate and a fixing point carriage, said plate having a series of parallel undercut grooves, fastening means on said carriage to secure the latter in adjusted position in one of said grooves, a fixing point on said carriage adapted to pierce and hold a pattern placed thereon, and a 125 130

punching arm removably hinged to said carriage, said punching arm having at one end thereof an aperture positioned and shaped to fit down over said fixing point.

- 5 6. In a device of the character described a fixing point carriage having a base unit, a holding plate formed with grooves for receiving the base unit of the fixing point carriage for adjustment thereon of said base 10 unit having a bearing surface above the upper surface of the holding plate and a fixing point on said unit adapted to pierce and hold a pattern placed thereon in spaced relationship to the holding plate.
- 15 7. In a device of the character described

a fixing point carriage having a base unit, a holding plate having grooves therein for receiving the base unit of the fixing point carriage of a pattern-grading machine, said base unit having a bearing surface above 20 the upper surface of the holding plate, a fixing point extending from the base unit adaptable to pierce and hold a pattern placed thereon, and a punching arm 25 removably hinged thereto, said punching arm having at one end thereof an aperture positioned and shaped to fit down over said fixing point.

In testimony whereof I affix my signature.

ADELARD J. THERRIEN.
